SET OF PLAYING CARDS

Marvin W. Smith, Box 506, Everett, Wash.

Filed Sept. 25, 1961, Ser. No. 66,825

Term of patent 14 years

(Cl. D34—13)

The FIGURE of the drawing is a plan view of the faces of a set of playing cards showing my new design.

The cards are of no appreciable thickness and the backs thereof are substantially plain. The deck consists of 4 suites of 15 cards, each suite being a different color, and a suite indicia is shown in broken lines.

I claim:

The ornamental design for a set of playing cards, substantially as shown and described.
